CLAIM

The ornamental design for a card and pinpad reader, as shown and described.

DESCRIPTION

FIG. 1 is a front perspective view of the card and pinpad reader in accordance with our new design;

FIG. 2 is a front elevational view thereof;

FIG. 3 is a rear elevational view thereof;

FIG. 4 is a right side elevational view thereof, the left side elevation view being identical;

FIG. 5 is a top plan view thereof; and,

FIG. 6 is a bottom plan view thereof.

The broken lines in the figures are for illustrative purposes only and form no part of the claimed design.
